DESIGN FOR A COAT

Morris Metzger, New York, N. Y.

Application August 22, 1936, Serial No. 64,526

Term of patent 3½ years

To all whom it may concern:

Be it known that I, Morris Metzger, a citizen of the United States of America, residing in city of New York, county of New York, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view of the coat shown in Fig. 1. My design is characterized by the stitched flaps on the front portion of the coat.

I claim:

The ornamental design for a coat substantially as shown and described.

MORRIS METZGER.
